UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed November 1, 1922. Serial No. 598,316.

To all whom it may concern:

Be it known that I, GEORGE M. LITTLE, a citizen of the United States, and a resident of Pittsburgh, in the county of Allegheny and State of Pennsylvania, have invented a new and useful Improvement in Electric Furnaces, of which the following is a specification.

My invention relates to furnaces and, particularly, to electric-resistance furnaces.

One object of my invention is to provide an electric furnace having a carbonaceous resistor which is enclosed in a substantially air-tight heating chamber.

Another object of my invention is to provide a refractory plate constituting a diaphragm above the resistor and a layer of finely divided carbonaceous material located on the diaphragm to protect the plate and also the resistor against oxidation, the thickness of the layer of granular carbonaceous material being in accordance with its exposure to oxidizing action.

Another object of my invention is to provide a built-up resistor comprising a plurality of relatively thin flat carbonaceous plates having non-current-carrying and weight-supporting extensions.

Another object of my invention is to provide a metallic water-cooled terminal electrode and a co-operating refractory elongated end block having provisions for maintaining them in axial alinement.

Carbonaceous resistors have a negative temperature coefficient of resistance and if a set of flat carbonaceous plates are in operative engagement over substantially their entire flat surface area and are supported directly by the furnace structure, that part of the plate immediately adjacent the support will operate at a higher temperature than the rest of the plate owing to the pocketing of the heat by the supporting structure. This higher temperature results in a lowered resistance permitting a larger portion of current to flow through this part of the plates thereby causing a still higher temperature at a part of the resistor where it is not wanted and where it may be detrimental. Another object of my invention is to provide a built-up supported carbonaceous resistor so constructed that the largest percentage of heat generated therein is pro-

duced in a portion of the resistor relatively distant from the support.

55

In the drawings,

Figure 1 is a view, in vertical longitudinal section, of a part of an electrical-resistance furnace embodying my invention;

Fig. 2 is a view, in vertical lateral section, 60 of a portion of an electrical furnace embodying my invention;

Fig. 3 is a fragmentary view, in vertical lateral section, of an electric furnace embodying my invention and comprising a 65 modified form of resistor;

Fig. 4 is a top plan view of the resistor illustrated in Fig. 3;

Fig. 5 is a view, in vertical lateral section, 70 of another modification of a resistor embodying my invention;

Fig. 6 is a top plan view of the resistor illustrated in Fig. 5;

Fig. 7 is a view, in vertical lateral section, 75 of another modification of a resistor embodying my invention;

Fig. 8 is a top plan view of the resistor illustrated in Fig. 7;

Fig. 9 is a view, in vertical lateral section, 80 of a still further modification of a resistor embodying my invention; and

Fig. 10 is a top plan view of the resistor illustrated in Fig. 9.

Referring more particularly to Figs. 1 and 2 of the drawings, a furnace structure, 85 designated generally by the numeral 11, embodies an outer lining 12 comprising side, end and bottom walls of any suitable refractory heat-insulating bricks or blocks. An inner lining 13 may be provided and 90 comprises a plurality of refractory high-temperature-resisting blocks or bricks, the inner-lining walls being so spaced apart as to provide a furnace chamber 14 of any suitable or desired contour and dimensions. 95

Heretofore, in an electric-resistance furnace operating at a relatively high temperature, it has been customary to place the carbonaceous resistor directly in the furnace chamber and to either enclose it in a substantially non-oxidizing container or to provide means, such as an inert gas, to prevent oxidation thereof. Another means for preventing oxidation of the carbonaceous resistor in furnaces having a work-receiving 100 opening to the furnace chamber, comprises 105

means for producing an accretive atmosphere or gas in the furnace chamber. It has also been found desirable in such furnaces to support the carbonaceous resistor free of the furnace walls in order to protect them against the relatively high temperatures.

In the present embodiment of my invention, I divide the furnace chamber into two parts and place the carbonaceous resistor in, 10 preferably, the lower part of the furnace chamber. A built-up heating element, designated generally by the numeral 15 in Figs. 1 and 2, comprises a plurality of relatively thin, flat, long, refractory carbonaceous plates 16 which are spaced apart by relatively short, thin, flat carbonaceous plates 17 alternating therewith, and located at the upper end of the long plates 16. The lower ends of the long carbonaceous plates 16 extend to substantially the bottom of the furnace chamber 14 and may rest on a flat refractory electrical-non-conducting plate 18.

A refractory, relatively elongated, carbonaceous end block 19 has its inner end operatively engaging one end of the built-up heating element 15. At its outer end, it is provided with an axial and longitudinally-extending bore 21 which is adapted to receive the inner end of a relatively small metallic water-cooled terminal electrode 22. The electrode 22 comprises a relatively thin-wall tubular member having its inner end so shaped as to conform to the shape of the bottom of the bore 21 in the end block 19. 30 The member 22 is provided with an inner, longitudinally-extending conduit 23 which, at its outer end, is secured to an end member 24 which has screw-threaded engagement with the outer end of the terminal electrode 22. Fluid inlet and outlet pipes 25 and 26 engage, respectively, the end member 24 and the conduit 23, and the tubular member 22 intermediate its ends, to permit of circulating a cooling fluid through the tubular member 23 to within a short distance of the inner end of the terminal electrode 22 and then outwardly through the outlet pipe 26.

Resilient means for pressing the terminal electrode 22, the end block 19, and the plates 16 and 17, into close operative engagement with each other comprises a helical spring 27, one end of which operatively engages the end member 24 and the other end of which is located in a socket member 28 having an insulating lining 29 therein. An adjusting screw 31, provided with a hand wheel 32 at its outer end, engages the socket member 28 and permits of varying the pressure applied between the various members of the built-up resistor, the end block and the terminal electrode.

A terminal lug 33 may be suitably secured against the terminal electrode 22 to permit of connecting one end of a supply circuit

thereto. If it is desired to employ only one heating-element, substantially as illustrated in Fig. 1 of the drawing, two end blocks 19 and terminal electrodes 22 may be employed therein located in axial alignment with each other and in opposite walls of the furnace. If it is desired to employ two resistors, the terminal members hereinbefore described may be located in the same wall of the furnace in spaced-apart relation, and the rear ends of the built-up resistors may be electrically connected by any suitable means, such as a carbonaceous plate which is pressed against the rear wall of the furnace by the action of the resilient compressing means hereinbefore described. The relatively deep axial bore 21 permits of locating a relatively large portion of the terminal electrode 22 therein whereby an alining effect of the electrode relatively to the end block 19 is obtained.

The water-cooling means hereinbefore described permits of operating the inner end of the metal electrode and the outer end of the end block 19 at a relatively low temperature but, if desired, I may provide means for still further reducing the oxidation of the outer end surface of the end block 19 by providing a well 34 so located in the walls of the furnace as to receive the outer end of the end block 19 and may place therein a mass 35 of finely divided granular carbonaceous material. It is, of course, understood that the end block 19 projects through a suitable opening in the furnace wall, as does also the metal electrode 22 to permit of their having longitudinal movement relatively to the wall of the furnace through which they extend. This construction permits of air entering the opening, and flowing past or along the outer surface of the metal electrode and the carbonaceous end block and, if the temperature of the carbonaceous block is relatively high, oxidation thereof will take place, an action which is substantially prevented by the granular material 35 surrounding it.

A refractory plate 36, which may comprise graphite, carborundum, alundum, fire-clay or substantially similar material, is located a short distance above the heating element 15. If the plate 36 is of graphite, it is placed in an inclined position relatively to the resistor to provide a sloping floor for a mass 37 of finely divided carbonaceous material, such as coke or charcoal. The upper surface of the mass 37 may be made substantially flush with the bottom of a work-receiving opening 38. It is, of course, apparent that the greatest oxidizing action of air entering the furnace chamber 39 within which material to be heat-treated is placed, will occur close to the work-receiving opening 38, and the depth of the granular carbonaceous material 37 is made

the greatest immediately adjacent to the opening 38. The operator can easily observe the amount of oxidizing action and the amount of granular material remaining, and fresh granular material may be easily introduced to replace that which has been destroyed by the oxidizing action.

If carborundum, alundum or fireclay plates are employed as diaphragms, they may be placed in a substantially horizontal position and no protecting layer of carbonaceous material is necessary.

Figs. 3 and 4 illustrate a modification of the resistor described in connection with Figs. 1 and 2 of the drawings, in which the relatively large resistor plates 16 extend in a substantially horizontal direction and are separated by alternating plates 17 of relatively small area of cross-section located intermediate the ends of the long plates. The outer ends of the large plates 16 may be supported on suitable shoulder portions 41 constituted by integral portions of the furnace walls which are so built as to provide these shoulder portions. Substantially the same results in operation are obtained from a built-up resistor in which the connecting plates 17 are located intermediate the ends of the relatively large or wing plates 16, as was hereinbefore described in connection with the modification illustrated in Figs. 1 and 2 of the drawings.

Figs. 5 and 6 illustrate a still further modification of a built-up resistor in which a relatively small number of wing plates 16 are employed and a relatively large number of smaller plates 17 which are, in turn, spaced apart by relatively narrow carbonaceous bars 42. The outer ends of the wing plates 17 may be supported on integral shoulder portions 41, as hereinbefore described in connection with the modification illustrated in Figs. 3 and 4. If the furnace is to be operated at a relatively high temperature, I may employ a plurality of bricks or blocks 43 to protect the side walls of the furnace chamber, locating them on integral shoulder portions 44, also constituted by the furnace wall structure.

Figs. 7 and 8 illustrate another modification in which wing plates 16 only are employed and are located at substantially right angles relatively to each other, with their upper ends operatively engaging each other and the lower ends operatively engaging either the bottom or the side walls of the furnace or both, as illustrated particularly in Fig. 7. It may be noted that the current-carrying area of each of the plates is relatively small in proportion to the total area of the plate.

Figs. 9 and 10 illustrate a still further modification in which wing plates 16 only are employed and are so located as to have only a portion of the flat surfaces of the

plates adjacent one end thereof in close operative engagement while the respective plates extend in substantially parallel and opposite directions. Blocks 45 of an electrical-non-conducting refractory material may be located above the outer ends of the respective sets of oppositely extending wing plates 16, upon which another refractory electrical-non-conducting plate 46 may be placed. The outer ends of the bars 16 may rest on refractory electrical-non-conducting blocks 47. A graphite diaphragm 36 may be supported by the plate 46 and a plurality of refractory electrical non-conducting bricks or blocks 48 located at the side of the furnace chamber. It is, of course, understood that the resilient compressing means described in connection with Figs. 1 and 2 is employed with all of these modifications.

The device embodying my invention thus provides a resistor for an electric-resistance furnace comprising a plurality of wing plates which are electrically conducting but are so arranged as to conduct current through only a relatively small portion thereof, the outer end of the wing plates serving to support the individual plate and the built-up resistor. The use of a graphite or carbonaceous diaphragm and also the use of finely divided oxidizable material located immediately above the diaphragm, permits of sealing the carbonaceous resistor effectively against the oxidizing action of air entering the portion of the furnace chamber which receives the work or material to be heat-treated.

The hereinbefore-described construction of a relatively small metal water-cooled electrode which fits into a carbonaceous or graphite terminal block results in obtaining an alining effect between the two members which is of value in maintaining the alinement of the built-up resistor, the terminal block and the metallic electrode with the resilient compressing means provided to maintain all of these members in close operative engagement under the varying operating conditions of the furnace.

This application is closely related to my copending applications Serial No. 598,317, filed November 1, 1922, and Serial No. 598,318, filed November 1, 1922, both assigned to the Westinghouse Electric & Manufacturing Company.

Various modifications may be made in the device embodying my invention without departing from the spirit and scope thereof, and I desire, therefore, that only such limitations shall be placed thereon as are imposed by the prior art or are specifically set forth in the appended claims.

I claim as my invention:

1. In an electric furnace, in combination, a built-up heating element comprising a

- plurality of refractory members, an elongated refractory end block operatively engaging said heating element and having a longitudinally-extending axial opening in its outer end, and a metallic terminal electrode operatively engaging said end block and extending into said axial opening.
2. In an electric furnace, in combination, a refractory heating element, an elongated refractory end block operatively engaging said heating element, and having a longitudinally-extending axial opening in its outer end, and a metallic terminal electrode operatively engaging said end block and extending into said axial opening.
3. In an electric furnace, in combination, a refractory heating element, an elongated refractory end block, of relatively large cross-sectional area, operatively engaging one end of said heating element and having a longitudinally-extending axial opening in its outer end, and a metallic terminal electrode, of relatively small cross-sectional area operatively engaging said end block and extending into said axial opening, whereby an axial alinement of said electrode and said end block and a relatively large area of contact therebetween is obtained.
4. In an electric furnace, in combination, a refractory heating element, an elongated refractory end block operatively engaging said heating element, and having a longitudinally-extending axial opening in its outer end, a water-cooled metallic terminal electrode operatively engaging said terminal block and extending into said axial opening and resilient means for maintaining said electrode, end block and heating element in close operative engagement with each other.
5. In an electric furnace, in combination, a heating element comprising a plurality of refractory members having integral non-current-carrying and weight-supporting extensions.
6. In an electric furnace, in combination, a heating element comprising a plurality of relatively thin refractory plates, each having one portion of relatively small area traversed by an electric current and another portion integral with said first portion for supporting the weight thereof.
7. In an electric furnace, in combination, a heating element comprising a plurality of relatively thin refractory plates each having integral non-current-carrying and weight-supporting extensions and resilient compressing means for maintaining said plates in close operative engagement with each other in said furnace.
8. In an electric furnace, in combination, a plurality of walls surrounding a furnace chamber, a refractory carbonaceous heating element in said chamber, a refractory carbonaceous diaphragm in said chamber dividing the same into two compartments, and a layer of finely divided carbonaceous material on said diaphragm for preventing access of air to said heating element.
9. In an electric furnace, in combination, a plurality of walls defining a furnace chamber, an opening in one of said walls adjacent the upper part of said chamber, a refractory carbonaceous heating element in the lower portion of said chamber, a refractory carbonaceous diaphragm in said chamber between said opening and said heating element, and a layer of comminuted carbonaceous material on said diaphragm, the thickness of said layer being a maximum adjacent said opening.
10. In an electric-resistance furnace, in combination, a furnace chamber having a work-receiving opening thereto, a refractory carbonaceous heating element in said chamber, a refractory diaphragm in said chamber between said work-receiving opening and said heating element, and a layer of heat-conducting comminuted granular oxidizable material on said diaphragm, the thickness of said layer being in accordance with the distance from said work-receiving opening.

In testimony whereof, I have hereunto subscribed my name this 27th day of October, 1922.

GEORGE M. LITTLE.
